MARINE STEERING APPARATUS

Fred C. Schoen, Roselle Park, N. J., De Witt F. Evans, Queens Village, N. Y., and Fred C. T. Schoen, Elizabeth, N. J.

Application November 27, 1944, Serial No. 565,278

5 Claims. (Cl. 114—144)

This invention relates to marine steering apparatus in which the winding drum for the tiller ropes is driven by a reversible rotary motor which is provided with a controller having a rotatable operating shaft.

The primary object of the present invention is to provide a marine steering apparatus of the above kind wherein the controller of the motor is operatively connected with the steering or pilot wheel so that the winding drum and the rudder will be actuated in a direction corresponding to the direction in which the steering wheel is turned, and wherein means driven by the winding drum is provided to automatically operate the controller so as to throw the motor out of operation and stop rotation of the winding drum when the latter has rotated to adjust the rudder a distance corresponding to the degree of turning movement imparted to the steering or pilot wheel.

Another object of the present invention is to provide a marine steering apparatus of the above character which permits location of the winding drum and its driving motor at a suitable point remote from the steering or pilot wheel, and wherein simple and efficient means is provided to limit the degree of turning movement which may be imparted to the steering or pilot wheel to thereby prevent operation of the motor to rotate the drum beyond a point dangerous to the rudder.

Still another object of the invention is to provide, in a marine steering apparatus, a compact, simple and efficient unit controllable by the pilot wheel to effect driving of the winding drum for the tiller ropes in the proper direction and to a proper extent to effect automatic adjustment of the rudder in accordance with the degree of movement imparted to the steering or pilot wheel.

The present invention consists in the novel form, combination and arrangement of parts hereinafter more fully described, shown in the accompanying drawings and claimed.

In the drawings, wherein like reference characters indicate corresponding parts throughout the several views:

Figure 1 is a rear elevational view of the unit forming the principal part of a marine steering apparatus constructed in accordance with the present invention.

Figure 2 is an enlarged side elevational view thereof looking toward the right of Figure 1.

Figure 3 is a top plan view of the construction shown in Figure 2, together with an operative connection between the unit and a steering or pilot wheel.

Figure 4 is an enlarged vertical longitudinal section taken on line 4—4 of Figure 1, and

Figure 5 is a vertical transverse section taken on line 5—5 of Figure 2.

Referring in detail to the drawings, the present steering apparatus embodies a unit that includes a suitable flat base 5 having spaced standards 6 mounted thereon at opposite sides thereof, said standards being provided at their upper ends

10 with transversely aligned bearings 7 in which are journaled the ends of a shaft 8 having a winding drum 9 secured thereon between the uprights 6. Secured on the shaft 8 at one end of drum 9 is a worm gear 10, and arranged beneath and meshing with the worm gear 10 is a worm 11. Rigidly mounted on the base 5 at the front of the latter is a conventional reversible rotary motor 12 having its power shaft directly connected with the worm 11 for driving the latter. The motor 12

20 may be of any suitable kind that has a controller provided with a rotatable operating shaft 13. By way of example, we have illustrated a compressed air motor of a well known kind that has been extensively used for the operation of drills and other purposes.

The controller of this type of motor is built in the motor casing and consists of a control valve which may be set to throw the motor out of operation when the shaft 13 is in one position, to cause operation of the motor in

30 one direction when the shaft 13 is turned in one direction, and to cause operation of the motor in the opposite direction when said shaft 13 is turned in an opposite direction. As the character and operation of this type of motor is well known in the art and forms no specific part of the present invention, detailed illustration and description thereof is deemed unnecessary herein. Also, it is quite evident that an electric or other motor may be used if provided with a rotatable controller

40 operating shaft corresponding to the shaft 13. The usual tiller ropes 14 and 14a, which may pass around guides 15, are connected in the usual way to the rudder and are respectively wound in opposite directions upon the opposite end portions 45 of drum 9. The motor 12 causes slow rotation of drum 9 through the gearing 10, 11, so as to cause turning of the rudder in the proper direction, depending upon the direction of operation of the motor.

50 Mounted on the base 5 adjacent one side of the latter and below the drum 9 are a pair of spaced brackets 16 and 17. A shaft is provided including a reduced smooth end portion 18 slidably and rotatably fitted in a bearing 19 at the top of bracket 17. The other or larger end portion of

this shaft is screw-threaded, as at 20, and extends freely through the bearing 21 at the top of bracket 16. Threaded on the end portion 20 of said shaft at the outer side of bracket 16 is a bevel gear 22 having a hub journaled in the bearing 21. A stop collar 23 is secured on the shaft portion 20 at the outer side of bevel gear 22. Journaled on the base 5 at the inner side of upright or standard 6, which is nearest the bevel gear 22, is a horizontal longitudinally disposed rock shaft 24 whose rear end carries an arm or lever 25 provided with a pivoted sleeve 26 fitted on the smooth shaft portion 18 against the adjacent inner end of the larger shaft portion 20. A pinion 27 is keyed on the shaft portion 18 at the inner side of collar 26 and in spaced relation to bracket 17. This pinion 27 meshes with a spur gear 28 secured on the shaft 8 at the end of drum 9 opposite that at which worm gear 10 is located. The other end of rock shaft 24 carries a spur gear 29 that meshes with a spur pinion 30 secured on a countershaft 31 journaled in bearing brackets 32 carried by the front end of base 5. Also secured on countershaft 31 is a bevel gear 33 that meshes with a bevel pinion 34 keyed on the controller shaft 13. Mounted on the outer side of the upright or standard 6 adjacent the bracket 16 is a shaft hanger or bracket 35 having vertically spaced bearings 36 in which the ends of a vertical feed screw 37 are journaled. Pinned on feed screw 37 directly under the upper bearing 36 is a collar 38, and arranged on said screw 37 directly beneath the collar 38 is a stationary nut 39. The adjacent faces of collar 38 and nut 39 are provided with interfitting ratchet teeth, as at 40, in Figure 2. The bottom face of nut 39 is provided with shouldered lugs 41. A collar 38a and a nut 39a, similar to the collar 38 and nut 39, respectively, are provided on the feed screw 37 directly above the lower bearing 36. The shouldered lugs 41a of nut 39a face in a direction opposite to that of the lugs 41 of nut 39. By turning nuts 39 and 39a, slight adjustment of the same toward or from each other and relative to the collars 38 and 38a may be had. Threaded on the feed screw 37 between the nuts 39 and 39a is a traveling nut 42 having oppositely facing shouldered lugs 43 and 43a on the opposite faces thereof. Traveling nut 42 engages the bracket 35 so as to be restrained against turning by the latter. The upper end of feed screw 37 is extended above the upper bearing 36 where it is provided with a keyway 44 to facilitate keying of a bevel gear thereon, as indicated at 45. Bevel gear 45 may be operatively connected with the steering or pilot wheel 46 through the medium of shafting 47 and bevel gears 48, or the like, thereby permitting actuation of feed screw 37 by turning the steering or pilot wheel 46, even though the latter is located at a point remote from the unit of which the feed screw 37 forms a part.

In operation, rotation of steering or pilot wheel 46 is transmitted to feed screw 37, thereby causing movement of nut 42 along feed screw 37 in a direction depending upon the direction in which the steering or pilot wheel 46 is turned. Obviously, the traveling nut 42 will ultimately contact either nut 39 or nut 39a so as to limit turning of the steering or pilot wheel 46 in either direction, for a purpose which will presently become apparent. Rotation of feed screw 37 is transmitted to gear 22 by the gear 49 secured on the lower end of feed screw 37 and meshing with said gear 22. As gear 22 is rotated, shaft 18, 20 is

5 moved longitudinally in one direction or the other, depending upon the direction in which gear 22 is turned. This is had because the shaft portion 20 has threaded engagement in gear 22 and the gear 22 is restrained against movement in a direction parallel with the axis of shaft 18, 20 or laterally toward or away from the adjacent bracket 16. Longitudinal movement of shaft 18, 20 and the pinion 27 keyed thereon causes actuation of collar 26 so as to swing arm 25 and rock the shaft 24. When shaft 24 is rocked, gear 29 is turned so as to rotate controller shaft 13 through the medium of gears 30, 33 and 34. Longitudinal movement of shaft 18, 20 in one direction causes actuation of rock shaft 24 so that controller shaft 13 is rotated to place the motor 12 in operation for driving drum in one direction. Longitudinal movement of shaft 18, 20 in the opposite direction causes rocking movement of shaft 24 in the opposite direction so as to turn controller shaft 13 in an opposite direction and cause motor 12 to drive the drum 9 in a reverse direction. This reverse drive of drum 9, of course, effects shifting of the rudder to one side or the other. As soon as the motor 12 is placed in operation, rotation of drum 9 is transmitted to shaft 18, 20 by gear 28 and pinion 27 in a direction opposite to that in which said shaft 18, 20 was just turned by actuation of steering or pilot wheel 46. This reverse rotation of shaft 18, 20 through the gearing with shaft 8 immediately causes actuation of rock shaft 24 so as to turn the controller shaft 13 back to a point where motor 12 is thrown out of operation. Thus, automatic means is provided, which is driven from the drum shaft for automatically throwing the motor 12 out of operation as soon as it has driven the drum 9 to a proper extent corresponding to the degree of movement which is immediately 30 previously imparted to steering or pilot wheel 46. The same operation is had regardless of which direction motor 12 is caused to drive the drum 9, so that the adjustment of the rudder is proportional to the degree of movement imparted to the wheel 46. It will be apparent that the engagement of traveling nut 42 with either nut 39 or nut 39a limits the extent to which the wheel 46 may be turned and thereby prevents operation of motor 12 to rotate the drum 9 beyond a point 40 dangerous to the rudder. The entire operation of the unit is automatic and under the sole control of steering or pilot wheel 46. The engagement of lugs 41 with lugs 43 or the engagement of lugs 41a with lugs 43a insure prompt and positive resistance to further turning of feed screw 37 after the steering or pilot wheel 46 has been rotated to its maximum permissible degree.

From the foregoing description, it is believed that the construction and operation, as well as the advantages, of the present invention will be readily understood and appreciated by those skilled in the art. It will be apparent that the invention is susceptible to such modifications and changes in the details of construction illustrated and described as fairly fall within the spirit and scope of the invention as claimed. A comparatively simple, compact and durable unit is provided which operates efficiently for the intended purpose.

70 What we claim as new is:

1. In a marine steering apparatus, the combination of a tiller rope drum, a reversible rotary motor operatively connected to said drum for driving the latter, said motor having a rotatable controller operating shaft adapted to be

turned in opposite directions to stop or control the direction of operation of the motor, a pilot wheel, means operatively connecting said pilot wheel with the controller operating shaft so as to rotate the latter in a direction corresponding to the direction of operation of the pilot wheel, and further means operatively connected to said first-named means and driven by the drum for turning the controller operating shaft in a direction reverse to that in which it has just previously been turned by actuation of the pilot wheel, whereby to automatically stop the motor and the drum after the latter has been operated to adjust the rudder to a degree corresponding to the degree of movement imparted to the pilot wheel.

2. In a marine steering apparatus, the combination of a tiller rope drum, a reversible rotary motor operatively connected to said drum for driving the latter, said motor having a rotatable controller operating shaft adapted to be turned in opposite directions to stop or control the direction of operation of the motor, a pilot wheel, means operatively connecting said pilot wheel with the controller operating shaft so as to rotate the latter in a direction corresponding to the direction of operation of the pilot wheel, and further means operatively connected to said first-named means and driven by the drum for turning the controller operating shaft in a direction reverse to that in which it has just previously been turned by actuation of the pilot wheel, whereby to automatically stop the motor and the drum after the latter has been operated to adjust the rudder to a degree corresponding to the degree of movement imparted to the pilot wheel, and means operatively associated with said first-named means to limit the turning of the pilot wheel in either direction so as to prevent operation of the motor to rotate the drum beyond a point dangerous to the rudder.

3. In a marine steering apparatus, the combination of a tiller rope drum, a reversible rotary motor operatively connected to said drum for driving the latter, said motor having a rotatable controller operating shaft adapted to be turned in opposite directions to stop or control the direction of operation of the motor, a pilot wheel, means operatively connecting said pilot wheel with the controller operating shaft so as to rotate the latter in a direction corresponding to the direction of operation of the pilot wheel, and further means operatively connected to said first-named means and driven by the drum for turning the controller operating shaft in a direction reverse to that in which it has just previously been turned by actuation of the pilot wheel, whereby to automatically stop the motor and the drum after the latter has been operated to adjust the rudder to a degree corresponding to the degree of movement imparted to the pilot wheel, and means operatively associated with

said first-named means to limit the turning of the pilot wheel in either direction so as to prevent operation of the motor to rotate the drum beyond a point dangerous to the rudder, said last-named means including a feed screw operatively connected to the pilot wheel, a travelling nut on said feed screw, means to restrain said traveling nut against rotation while permitting movement thereof longitudinally of the feed screw, and stop members carried by the feed screw at opposite sides of the traveling nut for engagement by the latter.

4. In a marine steering apparatus, a base, a tiller rope drum rotatably mounted on the base, a reversible rotary motor operatively connected to the drum for driving the latter, said motor being mounted on the base and provided with a rotatable controller operating shaft, a rock shaft mounted on the base and operatively geared to the controller operating shaft, a further shaft rotatably mounted and longitudinally movable on the base, means operatively connecting the last-named shaft with said rock shaft whereby rocking of the latter is caused by longitudinal movement of said last-named shaft, means to rotate said last-named shaft and to effect longitudinal movement thereof when rotated, and a driving connection between the drum and said last-named shaft for causing rotation of the latter in a reverse direction to that in which it has just been previously turned through the actuation of said last-named means.

5. In a marine steering apparatus, a rotatable feed screw, a pilot wheel, means operatively connecting the pilot wheel to said feed screw, a traveling nut on said feed screw, stop members for the feed nut carried by the feed screw at opposite sides of said traveling nut, a tiller rope drum, a reversible rotary motor operatively connected with the drum for driving the latter, said motor having a rotatable controller operating shaft, means operatively connecting the feed screw with said controller operating shaft, said last-named means including a rotatable and longitudinally movable shaft and means to longitudinally move said shaft when the latter is rotated, and means operatively connecting said rotatable and longitudinally movable shaft with the drum for turning the controller operating shaft in a direction reverse to that in which it has just previously been turned by the actuation of said feed screw, whereby to automatically throw the motor and drum out of operation after the drum has been driven sufficiently to adjust the rudder in correspondence with the degree of movement imparted to the pilot wheel, said traveling nut and said stop members coacting to prevent operation of the motor to rotate the drum beyond a point dangerous to the rudder.
